UNITED STATES PATENT OFFICE.

ROBERT M. HARDISON, OF BOSTON, MASSACHUSETTS, ASSIGNOR, BY MESNE ASSIGNMENTS, TO KALMAN STEEL COMPANY, OF CHICAGO, ILLINOIS, A CORPORATION OF DELAWARE.

FLAT-SLAB CONSTRUCTION.

Application filed February 27, 1922. Serial No. 539,373.

To all whom it may concern:

Be it known that I, ROBERT M. HARDISON, a citizen of the United States, and a resident of Boston, in the county of Suffolk and State of Massachusetts, have invented an Improvement in Flat-Slab Constructions, of which the following description, in connection with the accompanying drawings, is a specification, like characters on the drawings representing like parts.

This invention relates to reinforced concrete constructions and more particularly to flat-slab constructions, that is to say to that type of building construction employing a reinforced concrete slab in which the load upon the floor is carried directly to the slab-supporting member, which may be a concrete or other column or any other suitable support.

The invention and its aims and objects will be readily understood from the following description, taken in connection with the accompanying drawings of one illustrative embodiment of the invention, the invention in its true scope being more particularly set forth in the appended claims.

In the drawings:

Fig. 1 is a top plan view of one illustrative embodiment of the invention;

Fig. 2 is a lateral sectional elevation of the embodiment shown in Fig. 1;

Fig. 3 is a lateral sectional elevation of a modified construction; and

Fig. 4 is a lateral sectional elevation of a further modification.

Referring to the accompanying drawings, 2 indicates a concrete slab and 4 a concrete column. The head to be anchored in the slab will preferably comprise two spaced metal members, separated by one or more other metal members rigid therewith. In the embodiment of the invention herein illustrated, the head is indicated generally at 6, Fig. 1 and in its preferred form herein shown comprises a plurality of radially disposed members, herein twelve, said radial members herein consisting of I-irons 8. The advantage of so large a number of radial members is that they lie at relatively small angles to each other and thereby tend to minimize the concentration of stresses that would be incident to a small number of such members.

The I-irons 8 are embraced between two horizontal members or plates 10 and 12

which they separate and to which said I-irons are rigidly secured by any suitable means. Herein said I-irons are bolted to said plates 10 and 12 by bolts 14 extending through suitable openings provided in the flanges of said I-irons and in said plates. The free ends of the I-irons preferably project beyond the perimeters of the plates. The length of the I-irons projecting beyond the perimeters of the plates and the length of the I-irons embraced between said plates will be so proportioned as to provide ample opportunity for a connection between the I-irons and said plates which shall be of sufficient strength to resist any load or stresses to which said I-iron may be subjected without the possibility of separation or loosening of the connection of said plates and I-irons. In the embodiment of the invention herein shown, wherein the I-irons are bolted by their flanges to said plates, the length of the I-irons embraced between said plates is of sufficient length to provide space for the use of a number of bolts sufficient for this purpose.

The plates 10 and 12 and radial arms 8 might be integral, such as a casting for example, but I prefer the construction herein shown.

The plates 10 and 12 will preferably be provided with grout holes 16 and 18 respectively, herein preferably located centrally of said plates.

The head 6 may be used in conjunction with one or more metal members extending through it; any suitable reinforcing material or a metal column, for example, said member or members being encased within the concrete column. In Figs. 1 and 2 the head is shown as used in conjunction with a system of reinforcing rods 20, while in Figs. 3 and 4 the head is shown as used in conjunction with a metal column 22, which may be of steel, cast iron or any other suitable metal and of any suitable cross-section, such as an H- or I-iron, for example. In Figs. 1 and 2 the reinforcing metal rods 20 are shown as extending through suitable openings 24 preferably of the same shape as the cross-section of the rods 20 so as to fit the latter. They might extend through the grout holes, but the former construction is preferable. In Figs. 3 and 4 the steel column 20 is shown as extending through the grout holes 16, 18.

It will be noted that the members or plates 10 and 12 provide bearing areas within the perimeter of the column as indicated at 26, 26, which bearing areas take the loads transmitted from the floor panel.

It will also be understood by those skilled in the art that in a construction embodying this invention, when a load is applied at the ends of the radial arms tensile stresses occur in the top plate 10 and compression stresses in the bottom plate 12. Furthermore, in such case there is a tendency for the radial members to tear away from the plates. These conditions are completely met or counteracted by the provision of the bearing areas indicated and the connection of the radial members with the plates to form a unit, whereby the tensile and compression stresses caused by the loading of the arms are neutralized and the shearing stresses on a line at the junction of the column and the slab are resisted by the combined plates and radial members.

It will be noted that in the construction shown, the column or reinforcing rods being encased in the concrete, the stresses are transmitted through the concrete casing into the steel column or reinforcing rods.

In some cases projections or bearing areas may be attached to the steel column to receive the stresses from the concrete. Such projections or bearing areas are herein exemplified by angle irons 28 in Fig. 3, said angle irons being rigidly secured to the column 20 in any suitable manner as by bolts 29. Instead of these projections or bearing areas, or in conjunction therewith, a shelf may be secured to the column and the head rested on said shelf. Such a shelf is shown in Fig. 4, in the form of angle irons 30 suitably secured to the flanges of the column 20 in any suitable manner as by bolts 32.

As will be readily understood by those skilled in the art, by passing reinforcing members or rods 20 through the head, the head is anchored. A load applied at A produces compression on the concrete as indicated by the arrow at B, and in turn a tensile stress at the reinforcing member 20 as indicated by the arrow C. Likewise a load from above tends to stabilize the structure and produce compression in the concrete at D as indicated by the arrow.

Structures embodying my invention possess many advantages over those heretofore used. They are simple and economical in construction and their use makes it possible to do away with the capitals usually employed at the junction of the tops of interior columns with the under side of the slab or wall column brackets. This represents a substantial gain in space and eliminates the unsightly capitals or brackets heretofore considered necessary, so that my

invention is applicable to structures to be used for purposes for which the structures embodying the conical capitals or projecting wall brackets heretofore used are unsuitable or not desirable.

70

It will be apparent to those skilled in the art that my invention is applicable to columns and flat-slab constructions of all kinds and that it in no way interferes with the usual reinforcing employed in floors and columns and that any such reinforcing structure may be employed in conjunction with my invention. It will also be apparent that my invention will not interfere with the use of drainage or other pipes in the floor, the use of such pipes being perfectly feasible within floors of structures embodying my invention.

80

It will be apparent that it is not indispensable that all of the features of the invention be used conjointly, since they may be used to advantage separately in various combinations and sub-combinations. It will also be understood that, while the invention is herein described as embodied in the details illustrated, it is not to be considered as circumscribed by or limited to these details, or any of them, but that said details may be variously modified within the true scope of the invention which is definitely set forth by the claims.

85

90

95

What I claim is:

1. In a flat-slab construction, in combination, a concrete slab; a concrete column; a head encased in said slab and comprising two spaced metal plates and a plurality of I-irons embraced between said plates and rigid therewith, said members being radially disposed with respect to the center of said plates and at relatively small angles to each other; and one or more metal members extending through an opening or openings provided in said plates and encased in the concrete above and below said plates.

100

2. In a flat-slab construction, in combination, a concrete slab; a concrete column; a head encased in said slab and comprising two spaced metal plates wider than the column but having substantial bearing areas within the periphery of the column; and a plurality of metal members of angular section embraced between said plates and rigid therewith, said members being radially disposed with respect to the center of said plates and at relatively small angles to each other; and a metal column extending through an opening provided in said plates and encased in the concrete above and below said plates.

110

115

120

3. In a flat-slab construction, in combination, a concrete slab; a concrete column; a head encased in said slab and comprising two spaced metal plates wider than the column and having a central opening of small diameter than the column; and a plural-

125

130

ity of metal members embraced between said plates and rigid therewith, said members being radially disposed with respect to the center of said plates and projecting outwardly beyond the periphery thereof; a metal column extending through said opening provided in said plates and encased in the concrete above and below said plates; and a shelf projecting from the metal column and upon which rests said head.

4. In a flat-slab construction, in combination, a concrete slab; a concrete column; a head comprising two spaced metal members wider than the column and presenting bearing areas within the perimeter of said column and a plurality of longitudinal metal members embraced between said spaced metal members and extending radially outwardly therefrom, said longitudinal metal members being rigid with said spaced

metal members; and one or more metal members extending through said head and encased in the concrete above and below said head.

5. In a flat-slab construction, in combination, a concrete slab; a concrete column; a head comprising two spaced metal plates wider than the column and presenting bearing areas within the perimeter of said column and a plurality of longitudinal metal members embraced between said spaced metal plates and extending radially therefrom, said longitudinal metal members being rigid with said spaced metal plates; and one or more metal members extending through said head and encased in the concrete above and below said head.

In testimony whereof I have signed my name to this specification,

ROBERT M. HARDISON.
